UNITED STATES PATENT OFFICE.

WILLIAM J. SHACKELTON, OF SCOTCH PLAINS, NEW JERSEY, ASSIGNOR TO WESTERN ELECTRIC COMPANY, INCORPORATED, OF NEW YORK, N. Y., A CORPORATION OF NEW YORK.

SECRET SIGNALING SYSTEM.

Application filed September 4, 1919. Serial No. 321,694.

To all whom it may concern:

Be it known that I, WILLIAM J. SHACKELTON, a citizen of the United States, residing at Scotch Plains, in the county of Union, State of New Jersey, have invented certain new and useful Improvements in Secret Signaling Systems, of which the following is a full, clear, concise, and exact description.

19 This invention relates to secret signaling systems and more particularly to a system wherein telegraph currents are employed which are so small that they cannot be detected by ordinary signal receiving instruments but which are made audible in a telephone receiver by being continuously interrupted at an audible frequency.

In systems of this type which have been employed heretofore, difficulty has been experienced on account of sounds produced in the receiver by differences in ground potential between the receiving and sending stations. When these differences of potential are varying, as is often the case, 25 their effect cannot be eliminated by opposing a constant electromotive force thereto.

It is an object of the invention to provide an arrangement wherein the receiver will not be subject to the effects of ground potentials when signaling currents are not being passed therethrough.

In the embodiment of the invention herein disclosed, the receiver is arranged to be in series with the telegraph key, and because of this arrangement, currents can not flow through the receiver except when the key is closed. The receiver, therefore, is not affected by ground potentials when the key is opened. When the key is closed, the 40 ground potentials are not detrimental since they are merely added to or subtracted from the potential of the set battery.

A further object of the invention is to provide efficient means for interrupting the 45 signaling currents to obtain the maximum response in the receiver, and associated therewith means for sending out on the line currents of suitable frequency and amplitude for calling a distant station.

These and other objects of the invention 50 will be more fully understood from the following detailed description and claims taken in connection with the accompanying drawings in which--

Fig. 1 represents diagrammatically a cir-

cuit embodying the invention, the switches being in the proper position for calling;

Fig. 2 shows the circuit of Fig. 1 in condition for sending;

Fig. 3 shows the circuit of Fig. 1 in condition for receiving;

Fig. 4 shows a circuit adapted to be used where ground potentials are not rapidly varying, the circuit being in normal condition for receiving a call;

Fig. 5 shows the circuit of Fig. 4 in condition for calling, and

Fig. 6 shows the circuit of Fig. 4 in condition for sending or receiving.

In all of the above diagrams, the portions of the circuit containing line currents are shown in heavy full lines, and the portions containing local currents are shown in heavy dotted lines.

Referring to Figs. 1, 2 and 3, the line 10 is adapted to be connected to the filter 11, telegraph key 12, resistance 13, batteries 14 and 15, carbon button 16 and receiver 17 to ground at 18. The filter 11 comprises series inductances 19 and shunt condensers 20. 60 The switches 21 and 22 may be opened when signals are not being sent in order to avoid wastage of battery energy. Switch 23 may be closed to provide a shunt path around condenser 28 when receiving signals. Condenser 28 provides a path for local current when sending, as will be later explained.

Means for continuously varying or chopping the signaling currents is provided which comprises the carbon button 16, carbon button 24, telephone receiver or electromagnet 25, condenser 26 and the battery 15. The filter 11 is so designed with reference to the frequency of the fluctuating current, that it will prevent the passage of such 95 frequencies. The diaphragm of receiver 25 is in contact with the button 24, and when switch 22 is closed, continuous fluctuations of current at an audible frequency through the button 24 are produced. The mechanical 100 movements of the button 24 are imparted to the button 16 and so produce similar fluctuations in any currents which may be passing through the button 16. The purpose of this will be explained later on.

The two point switch 27 is provided to connect the filter 11 between the line and the branch including the receiver 17, or to connect the receiver in series with the line and one of the condensers 20.

In the line 10 is placed the secondary 31 of transformer or induction coil 30, which may be of the Rumkorff type. The primary circuit of the induction coil comprises 5 the primary 32, the interrupter 33, condenser 34, switch 35, and batteries 14 and 15. When the switch 35 is closed, calling currents of a suitable strength and frequency for producing a loud sound in a receiver at 10 a distant station are sent out on line 10. When a call is being sent switch 36 may be closed to short-circuit the apparatus between secondary 31 and ground 18.

When it is desired to use the line for 15 telephony, a transmitter 40 and a receiver 41 may be plugged in, the former being connected across the primary 32 and the battery 14 and the receiver directly in series with the grounded part of the line and 20 with one of the condensers 20. It will be seen that the induction coil 30 serves as a transformer when telephone messages are being sent, and that received telephone messages are not required to pass through in- 25 ductances 19 of the filter 11.

The operation of the circuit for secret telegraphy is as follows:

For sending a call, the switches are in 30 the positions shown in Fig. 1, the induction coil 30 serving to transmit the calling current. Switch 35 serves as a key for closing batteries 14 and 15 through the primary of the induction coil. The normal position for receiving a call is like that 35 shown in Fig. 1 except that the switches 35 and 36 are open. The received calling currents pass through one or more of the condensers 20 which are in series with receiver 17 and produce a loud sound in the 40 receiver.

When sending telegraph messages the circuit is shown in Fig. 2. The telegraph key 12 is operated and small direct current impulses corresponding to a suitable signaling code, such as the Morse code, are sent out 45 through the filter 11 on the line 10. The strength of the current may be regulated by resistance 13 and should be so feeble that it cannot be detected by the most sensitive 50 relays employed in telegraphy. The distant station, however, is provided with means for chopping or varying the currents so as to render them audible in a telephone receiver. This means is similar to the arrangement at the sending station, the operation of which will now be described.

The signal currents pass through button 55 16 at the sending station shown in Fig. 2, and through a similar button at the receiving station. These buttons are continuously vibrated by the armatures of electromagnets 25, and by reason of the changing resistance of the button continuous fluctuations of current are set up. For most 60 efficient operation, it has been found that

these fluctuations should be at a considerable higher frequency than the frequency of the calling currents produced by induction coil 30. The chopper at the distant station renders the signal currents audible 70 in a receiver at that station and the chopper at the sending station renders them audible in the receiver 17, thus affording the sending operator means for determining whether signals are being properly transmitted or 75 not. The filter 11 is provided to prevent the current fluctuations from passing out to the line where they might be heard by an unauthorized person.

The local circuit for the alternating component of the current is provided by the condenser 28, one or more of condensers 20 and the switch 27. It will be seen that, when sending, switch 27 is thrown to the left, connecting the condensers 20 from the line to ground and thereby putting them in proper position to function as a part of the filter. Switches 21 and 22 are, of course, closed and switch 23 is opened.

When receiving, switch 23 is closed and feeble direct current signals from the distant station pass through the chopper button 16 and receiver 17 where they are made audible as above described. The flow of 90 signal current during reception is shown in 95 heavy full lines in Fig. 3.

It will be seen that in the circuit, as in Fig. 2 or in Fig. 3, currents can pass through the receiver 17 only when the telegraph key at the same station or at a distant station is closed. There is thus no possibility of sounds being produced in the receiver 17 when neither key is closed by reason of differences in ground potential 100 between the two stations. Ground potentials only act in series with the set battery and act to increase or decrease the strength of signals, but do not cause tone during silent intervals.

Referring to Figs. 4, 5 and 6, the line 10 is connected through filter 11' which is similar to filter 11 and then to ground through parallel paths, one of which includes the telegraph key 12' and the other of which includes receiver 17' and carbon button 16'. Condenser 45 and switch 48 are provided to form a local circuit with receiver 17' and button 16' for alternating currents produced by the chopper, which is similar to that shown in Fig. 1. A local circuit for direct currents through the receiver when transmitting comprises the switch 47 and resistance 46, which is employed to equalize the impedance of this circuit with that of the line.

A single battery 14' is employed to actuate the chopper and the induction coil 30' and also to furnish the signaling currents. The two point switch 50 is employed to throw the battery from the primary circuit 125 130

or induction coil to the chopper circuit and telegraph key. The switch 51 may be closed to short-circuit the secondary of the induction coil for receiving a call.

3. Since in this form, receiver 17' is permanently connected across the line, a battery 52 with potentiometer 53 and switch 54 is employed to oppose any steady ground potentials which may be found to exist.

10 As shown in Fig. 4, in the normal position of the circuit, calling currents pass through to the first condenser 20, condenser 45, receiver 17' and thence to ground through the shunt path comprising the 15 switch 51, all other switches being open as shown. When a call is to be sent, switch 48 is closed as shown in Fig. 5 and switch 50 is thrown to close the primary circuit of the induction coil 30'. Switch 51 is opened.

20 The secondary circuit for the calling currents will be seen to include the shunt path through switch 48.

The position of switches for sending or receiving messages is the same and is shown 25 in Fig. 6, switch 50 being thrown to the upper position so as to operate the chopper button 24. Switch 47 is closed so that part of the current may pass through receiver 17' when sending, for the purpose above explained.

30 It will be understood that both in the form shown in Fig. 1 and in Fig. 4, the switches may be arranged to be operated by a common turn button or handle, but are shown separate in the drawings merely for the purpose of simplifying the circuit diagrams.

The invention is not limited to the specific forms shown and described, but is entitled to 40 equivalents within the scope of the appended claims.

What is claimed is:

1. In combination, a line, and a station comprising a wave filter, a telegraph key, a 45 source of signaling current, continuously op-

erable means for producing fluctuations of current, and a receiver, said elements being connected in series with each other, said filter being interposed between said line and the part of the circuit containing said continuously operable means and said receiver. 50

2. In a signaling system, a receiver and means in series therewith for continuously varying the current therethrough, a line, means to prevent said variations from passing to said line, a telegraph key at a distant station, a source of current, and connections so arranged that, on receiving, the line circuit is closed to direct current only when 55 said distant key is closed. 60

3. A signaling system comprising a line, a filter, a telegraph key, a receiver, and means for connecting said receiver in series with said key and for connecting said filter between said receiver and said line when 65 signals are being transmitted and means for changing the circuit connections between said filter and said receiver when a call is to be received.

4. A signaling system comprising a line, 70 a receiver, a filter comprising an inductance and a capacity, and means for connecting said receiver to said line at times so that line currents flow to said receiver principally through said inductance and at other times 75 so that line currents flow to said receiver principally through said capacity.

5. In a signaling system, a line, a filter connected thereto, means providing at times a path in shunt to said line and to a path including said filter, means for continuously varying currents passing through said filter, a receiver in series with said means, and separate means for producing calling current and transmitting said calling current 85 in said shunt path. 80

In witness whereof I hereunto subscribe my name this 28th day of August, A. D. 1919.

WILLIAM J. SHACKELTON.
